UNITED STATES PATENT OFFICE.

ERIC R. LUNDIUS, OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,296,677.

Specification of Letters Patent. Patented Mar. 11, 1919.

Application filed May 3, 1918. Serial No. 232,269.

To all whom it may concern:

Be it known that I, ERIC R. LUNDIUS, a citizen of the United States, residing at Brooklyn, in the county of Kings, State of New York, have invented certain new and useful Improvements in Telephone-Exchange Systems, of which the following is a full, clear, concise, and exact description.

This invention relates to telephone exchange systems and more particularly to such systems of the central energy type which employ automatic ringing for signaling purposes, and which are equipped with trunk circuits extending to private branch exchanges, chief operators' desks and like positions.

In systems of this type employing trunk circuits extending from a switchboard position to a chief operator's or information operator's desk and coöperating at the switchboard position with an automatic ringing link circuit, it is usual to cause the disconnection of ringing current from the trunk circuit upon connection being made therewith at the answering or incoming end. There is usually considerable disturbance in the talking circuit attending the disconnection of the ringing current and the substitution of the direct current therefor, which, if the answering operator's receiver be connected to the talking circuit, produces very severe clicks in the receiver. It is an object of this invention to provide a system of this character in which the receiver of the answering operator is not connected with the talking circuit until after ringing current has been disconnected and direct current substituted therefor, thereby practically eliminating all disturbance in the receiver of the answering operator. It is also an object of this invention to provide improved signaling means for systems of this character.

In accordance with this invention the ringing current is automatically connected with the trunk circuit upon the connection of the link circuit therewith and upon connection being made with the trunk circuit at the incoming end, apparatus responds to connect across the trunk circuit a low impedance bridge for causing the disconnection of the ringing current from the trunk circuit, after which the normally open talking conductors of the trunk circuit are closed to extend the talking circuit to the desk.

For a more complete understanding of this

invention, reference should be had to the following description considered in connection with the accompanying drawing illustrating one embodiment thereof.

There is shown in the drawing an automatic ringing link circuit A located at a switchboard position, from which a trunk circuit B extends to an operator's desk, or other switchboard position. At the desk there is located a cord circuit C, by means of which connection may be made with the incoming end of the trunk circuit. The apparatus shown to the left of the dotted line 1-1 is located at the switchboard X, and that located to the right of the dotted line 1-1 may be located at the desk or second switchboard Y.

The nature of this invention is such that it is thought that it will be clearly understood from a description of the operation of the system disclosed in the drawing and it will be so described.

The originating operator desiring to establish a connection by way of the trunk circuit with the desk operator, inserts plug 5 of the cord circuit A into jack 6 of the trunk circuit B, whereupon lamp 7 lights and relays 8 and 9 operate over a circuit from battery through the lamp 7, winding of relay 8, sleeve contacts of the plug 5 and the jack 6, contact 10 of relay 11, winding of relay 9 and contact 12 of relay 11 to ground. Relay 8, in operating, causes the operation of ringing relay 13 over a circuit from battery through resistance 14, winding of ringing relay 13, normal contact of relay 15, contact of tripping relay 16 and the contact of relay 8 to ground. The operation of ringing relay 13 connects a source of ringing current 17 through the winding of the tripping relay 16 to the trunk circuit B. The operation of relay 9 causes the lighting of lamp 18 over a circuit from battery through the lamp 18, contact 19 of relay 11 and the contact of relay 9 to ground.

The desk operator observing the lighted condition of the lamp 18 inserts plug 25 of the cord circuit A into jack 26 of the trunk circuit B, whereupon the lamp 27 is lighted and relay 28 operated over a circuit from battery through the lamp 27, resistance 29, sleeve contacts of the plug 25 and the jack 26, lower winding of relay 28 and contact 30 of relay 31 to ground. Relay 28, in operating, short-circuits condenser 32 and connects

the three windings of retardation coil 33 directly in bridge of the talking conductors of the trunk circuit B. The right and left-hand windings of this retardation coil 33 are 5 of low impedance, while the middle winding is of high impedance. The tripping relay 16 will not operate when the three windings of the retardation coil 33 are connected in series therewith. Relay 28, in operating, also 10 causes the operation of relay 11 over a circuit from battery through the lamp 7, winding of relay 8, sleeve contacts of the plug 5, the jack 6, contact 34 of relay 28 and the winding of relay 11 to ground. Relay 11, 15 in operating, opens the circuit of and effaces the lamp 18, removes relay 9 from the sleeve conductor, thereby deenergizing this relay 9, and by the closure of its contact 35, connects relay 9 in parallel with the middle or high 20 impedance winding of the retardation coil 33. The closure of contact 36 of relay 11 establishes a locking circuit therefor, thereby rendering this relay independent of the condition of relay 28. The connection of relay 25 9 in parallel with the high impedance winding of the retardation coil 33 lowers the impedance of the bridge to such an extent that the tripping relay 16 operates.

The tripping relay 16, in operating, 30 removes the short circuit from the winding of the relay 15, which thereupon operates, locks up and establishes a short circuit for the ringing relay 13, which is thereupon deenergized to disconnect the source of ringing 35 current from the trunk circuit B. Ringing relay 13 in closing its normal contacts connects a source of direct current with the talking conductors of the trunk circuit.

Relay 9 is responsive to direct current but 40 is non-responsive to ringing current. That is, while there is a partial attraction of the armature of relay 9 when its winding is traversed by ringing current, this attraction is not sufficient to permit the continued closure 45 of its contact. Upon the disconnection of ringing current from the trunk circuit B, a source of direct current is substituted therefor so that the relay 9 then operates over a circuit from battery through the 50 winding of supervisory relay 40, lower normal contact of ringing relay 13, ring contacts of the plug 5 and the jack 6, left-hand winding of impedance coil 33, contact 35 of relay 11, winding of relay 9, right-hand winding 55 of retardation coil 33, contact 41 of relay 28, tip contacts of the jack 6 and the plug 5, upper normal contact of the ringing relay 13 to ground. Relay 9, in operating, causes the operation of a slow-release relay 42 over a 60 circuit from battery through the normal contact of slow-release relay 43, normal contact of relay 44, winding of slow-release relay 42, contact 45 of relay 11 and the contact of relay 9 to ground. Relay 42, in operating, 65 causes the operation of relay 44 over a cir-

cuit from battery through the right-hand contact of relay 42, winding of relay 44, contact 45 of relay 11 and the contact of relay 9 to ground. Relay 44, in operating, completes a locking circuit for itself from battery through the normal contact of relay 43, right-hand alternate contact and winding of relay 44, contact 45 of relay 11 and the contact of relay 9 to ground. The operation of relay 44 opens the circuit of relay 42, which 70 thereupon releases its armature. Upon the closure of the left-hand contact of relay 42, relay 31 operates over a circuit from battery through the winding of relay 31, left-hand alternate contact of relay 44, left-hand contact of relay 42, contact 45 of relay 11 and the contact of relay 9 to ground. Relay 31, in operating, opens its contact 30, thereby removing the short circuit from the upper winding of relay 28, which increases the resistance in circuit with the lamp 27 to such an extent that the lamp is effaced. Relay 31, in operating, also closes normally open contacts in the talking conductors of the trunk circuit. Upon the closure of the circuit 85 through supervisory relay 40, this relay operated, establishing about the lamp 7 a shunt circuit including resistance 14 for effacing the supervisory lamp 7. The originating operator may thereupon actuate listening key 90 46 to connect the telephone set in circuit. The desk operator may actuate listening key 47 to connect the desk operator's telephone set in circuit, that is, if this listening key 47 had not been previously actuated prior to or 95 immediately after the plug 25 was inserted in the jack 26. Since both operators' telephone sets are now connected in circuit, the operators may converse. At the conclusion 100 of their conversation, the withdrawal of the 105 plugs from the jacks restores all apparatus to normal condition.

If the desk operator's telephone set is not connected in circuit at the time the originating operator's set is connected with the trunk 110 circuit, the originating operator may resign the desk operator by causing the flashing or intermittent glow of the lamp 27. This is brought about by the repeated withdrawal of the plug 5 from and the insertion 115 thereof into the jack 6. Upon the withdrawal of the plug 5 from the jack 6, relays 9, 11, 44 and 31 release their armatures. The release of relay 31 closes its contact 30, thereby short-circuiting the upper winding 120 of relay 28. The resistance in circuit with the lamp 27 is thereby reduced to such an extent that the lamp lights. The closure of the upper and lower normal contacts of relay 31 establishes a short circuit about each 125 of the condensers 48 and 49, thereby to provide discharge paths for these condensers, so that when the normally open contacts in the talking conductors are closed upon the subsequent energization of relay 31, there will 130

be no discharge from the condensers over the talking circuit. The connecting of these condensers in circuit with the talking conductors when in their discharged condition prevents disturbance in the talking circuit. The reinsertion of the plug 5 into the jack 6 causes the operation of relays 8 and 9, as before. Relay 8 operates the ringing relay to connect ringing current with the trunk circuit, and relay 9 may light the lamp 18 momentarily but for no longer, for relay 11 operates practically simultaneously with the operation of relay 9, and in so doing, opens the operating circuit of the lamp 18 and the energizing circuit of relay 9. Relay 11, in operating, also connects the relay 9 in shunt of the high impedance winding of the retardation coil 33, thereby to cause the operation of the tripping relay 16 and the consequent disconnection of the ringing current from the trunk circuit, in the manner hereinbefore described. Relay 9 then operates to energize the slow-release relay 42, whereupon relay 44 is energized and locked up to release relay 42. Upon the release of this relay, relay 31 operates in the manner already described to complete the talking circuit. Each time the plug 5 is withdrawn from the jack 6, the lamp 27 is lighted and the intermittent lighting of this lamp serves as a signal to the desk operator, who, upon observing the flashing thereof, may actuate the listening key 47 to connect the telephone set in circuit.

If a calling telephone line (not shown) is connected by way of the automatic ringing cord circuit A and the trunk circuit B with the desk operator's cord circuit C, the desk operator may converse directly with the calling subscriber. After furnishing to the subscriber such information as is desired, the desk operator may wish to signal the originating operator. This may be done by the repeated actuation of key 50, to cause the flashing or intermittent operation of the supervisory lamp 7 of the cord circuit 8. The actuation of the key 50 by the closure of the upper contact, short-circuits the windings of relay 28, thereby causing this relay to release its armatures to open up the direct current bridge of the talking conductors which includes retardation coil 33 and relay 9. Supervisory relay 40 thereupon releases its armature to remove the shunt circuit from about lamp 7. This lamp 7 thereupon lights. The closure of the lower contact of the key 50 energizes the slow-release relay 43, which opens its normal and closes its alternate contact. The opening of the normal contact of relay 43 prevents the energization of relay 42 after relay 44 has released its armatures, following the deenergization of relay 9. The closure of the alternate contact of relay 43 prepares an energizing circuit for relay 44 which is independent of the relay 42. Relay

9 releases its armature upon the opening of the direct current bridge of the talking conductors, and in so doing, opens the circuits of relays 31 and 44 which thereupon release their armatures. The relay 31, in releasing 70 its armatures, opens the talking conductors of the trunk circuit. Upon the restoration of the key 50 to normal position, the short circuit is removed from the lower winding of relay 28 which thereupon operates, 75 re-establishing the direct current bridge of the talking conductors. Relay 40 and relay 9 thereupon operate, the former causing the effacement of the lamp 7 and the latter causing the operation of relay 44. Relay 44, in 80 operating, causes the energization of relay 31, which removes the short circuit of the upper winding of relay 28 and closes the normally open contacts of the talking conductors. Relay 43 being slow to release, 85 maintains its alternate contact closed after the opening of the lower contact of the key 50, until the contact of relay 9 is closed. Therefore, relays 28, 9, 44 and 31 are the only relays which function to control the 90 opening and the closure of the talking conductors while the desk operator is signaling the originating operator. The lamp 7 is lighted each time the key 50 is actuated, and the intermittent lighting of this lamp serves 95 as a signal to the originating operator that the desk operator is calling. The length of time required for these relays to function is such that the desk operator's telephone set is connected in circuit, upon each restoration of the key 50 to normal position, so that if the originating operator, observing the intermittent operation of the lamp 7, connects her telephone set in circuit by the actuation of the listening key 46, the desk operator may hear the originating operator answering and stop the repeated actuation of the key 50.

What is claimed is:

1. A telephone exchange system comprising a trunk circuit extending from a first to a second switchboard, a link circuit at the first switchboard, a source of ringing current, means responsive to the connection of the link circuit with the trunk circuit for 110 connecting a source of ringing current therewith, a link circuit at the second switchboard, a relay responsive to the connection of the second link circuit with the trunk circuit, and a low impedance bridge for the 115 trunk circuit established upon the response of the relay for causing the disconnection of the source of ringing current from the trunk circuit.

2. A telephone exchange system comprising a trunk circuit having normally open talking conductors extending from a first to a second switchboard, a link circuit at the first switchboard, a source of ringing current, means responsive to the connection of 125

- the link circuit with the trunk circuit for connecting the source of ringing current therewith, a signal control relay in the trunk circuit responsive to the connection of the 5 link circuit therewith, a link circuit at the second switchboard, means responsive to the connection of the second link circuit with the trunk circuit for connecting the signal control relay in bridge of the talking conductors, means in the first link circuit responsive to the connection of the signal control relay in bridge of the talking conductors for disconnecting the source of ringing current from the trunk circuit, means for 10 thereafter energizing the signal control relay over the talking conductors, and means responsive to the energization of the bridged relay for closing the normally open talking conductors.
- 20 3. A telephone exchange system comprising a trunk circuit extending from a first to a second switchboard, a link circuit at the first switchboard, a source of ringing current, means responsive to the connection of 25 the link circuit with the trunk circuit for connecting the source of ringing current therewith, a signaling device at the second switchboard, a relay energized upon the connection of the link circuit with the trunk circuit for operating the signaling device, a link circuit at the second switchboard, a relay operating upon the connection of the second link circuit with the trunk circuit to deenergize and connect the first relay in 30 bridge of the talking conductors, and means in the link circuit responsive to the connection of the first relay in bridge of the talking conductors for disconnecting the source of ringing current from the trunk 35 circuit.
- 40 4. A telephone exchange system comprising a trunk circuit having normally open talking conductors extending from a first to a second switchboard, a link circuit at the first switchboard, a source of ringing current, means responsive to the connection of 45

the link circuit with the trunk circuit for connecting the source of ringing current therewith, a link circuit at the second switchboard, a relay connected in bridge of the talking conductors upon the connection of the second link circuit with the trunk circuit, means in the first link circuit responsive to the connection of the relay in bridge of the talking conductors for disconnecting the source of ringing current from the trunk circuit, a source of direct current connected with the trunk circuit upon the disconnection of the source of ringing current for energizing the bridged relay, and a relay responsive to the energization of the bridged relay for closing the normally open talking conductors.

5. A telephone exchange system comprising a trunk circuit having normally open talking conductors extending from a first to a second switchboard, a link circuit at the first switchboard, a source of ringing current, means responsive to the connection of the link circuit with the trunk circuit for connecting therewith the source of ringing current, a signal control relay operating upon connection of the link circuit with the trunk circuit, a link circuit at the second switchboard, a relay operating upon the connection of the second link circuit with the trunk circuit for releasing and connecting the signal control relay in bridge of the talking conductors, means in the first link circuit responsive to the connection of the 65 signal control relay in the bridge for disconnecting the source of ringing current from the trunk circuit, means for thereafter energizing the bridged relay over the talking conductors, a relay for closing the 70 normally open talking conductors, and a slow-release relay coöperating with the bridged relay for delaying the energization of the talking conductor control relay.

In witness whereof I hereunto subscribe my name this 27th day of April, A. D. 1918.
ERIC R. LUNDIUS.
